UNITED STATES PATENT OFFICE.

ALEXANDER G. MCKENNA AND WILLIAM DALTON, OF WASHINGTON, DISTRICT OF COLUMBIA, ASSIGNORS TO WASHINGTON STEEL & ORDNANCE COMPANY, OF WASHINGTON, DISTRICT OF COLUMBIA, A CORPORATION OF WEST VIRGINIA.

ARMOR-PIERCING PROJECTILE.

1,301,859.

Specification of Letters Patent. Patented Apr. 29, 1919.

Application filed June 12, 1917. Serial No. 174,347.

To all whom it may concern:

Be it known that we, ALEXANDER G. MCKENNA and WILLIAM DALTON, citizens of the United States, residing at Washington, 5 in the District of Columbia, have invented certain new and useful Improvements in Armor-Piercing Projectiles; and we do hereby declare the following to be a full, clear, and exact description of the same, 10 when taken in connection with the accompanying drawings, forming part of this specification.

This invention relates to armor piercing projectiles and specifically to that part of 15 such projectiles designated as the cap. Caps for such projectiles serve to facilitate the passage of the body of the projectile through 20 resistant protective armor and are commonly made of metal which is tough but soft or ductile as compared with the projectile itself or the nose of the projectile, although it has 25 been proposed to form such caps with a hardened striking portion integral with the body of the cap. Practical experience and tests show that the armor piercing qualities 30 are enhanced by hardening the nose or striking portion of the cap and the present invention is designed not only to still further enhance the armor piercing qualities of the 35 projectile, but to provide a structure which can be conveniently and easily manufactured and which will embody a uniformity in structural characteristics not practically attainable when an integral metal cap is made part hard and part soft as in the prior caps referred to.

In carrying the invention into practice, 40 the cap which may have any approved contour lines is built up of separate sections extending transversely of the axis of the cap, the several sections being of different degrees of hardness. The meeting or mating 45 portions of the several sections are so formed or the sections are so connected that premature relative displacement will not occur even under oblique impact at any angle where the projectile could be effective and in the preferred construction the hardness of the sections increases progressively toward 50 the nose or striking part of the cap.

In the accompanying drawings:

Figure 1 is a section longitudinally of a cap embodying the present invention, the

front end of the body of the projectile being shown in outline. 55

Fig. 2 is a similar view showing a modification.

The front end of the body of an armor piercing projectile is indicated at A and the several sections of the cap are shown in section at B, C and D, respectively. The contour lines of both the body of the projectile and of the cap adopted for illustrating the invention are conventional and in practice will conform to regulation or preferred 60 contour lines which, as is well understood in the art, is subject to variation and depends in a measure upon the designed use of the projectile. 65

The several sections B, C, D are superposed one upon the other longitudinally of the axis of the projectile and each therefore extends transversely of the axis. Their meeting or mating faces are preferably so formed that harmful relative lateral displacement will not occur prematurely even under force created by oblique impact at any angle where the projectile could be effective and this result is best attained by making the said faces conical or tapering in a forwardly direction as shown at b, c. To still further guard against such displacement it is preferred that the degree of taper shall increase toward the front or striking end of the cap, thus the meeting faces of the sections C and D form, as shown at c, a rather sharp cone while the proximate faces of the sections B and C form a rather blunt cone. In other words, the radius of the angle decreased toward the front of the cap. 90

The several sections may be normally held in proper relative position in a variety of ways, two only of which are illustrated. In Fig. 1 the peripheral edges of the meeting faces are joined by an electric welding process as indicated at E, while in Fig. 2 screw threaded projections and co-operating sockets are formed axially of the sections as indicated at G. 95

With the present construction each section may be formed of metal having the desired characteristics or the metal of each section may be separately treated to give it the desired characteristics as to hardness, toughness, etc., without affecting the 105 characteristics of the other sections. Each

section being formed separately absolute uniformity in results can be attained.

In the preferred construction the degree of hardness of the several sections increases progressively toward the striking end or nose, the extreme end section being comparable in hardness with the nose of the body of the projectile while the rear section is comparable in hardness and toughness 10 with the so-called soft metal caps in common use.

The increased efficiency of the projectile is believed to be due, in part, at least, to the successive action of the hard noses of the 15 cap and body of the projectile, resulting first in a partial and then a complete rupture of the armor plate under attack and at the same time the advantageous effects of 20 a soft metal cap are preserved. In the results attained it would seem that the energy stored in the metal of the cap is caused to perform useful work in rupturing the attacked armor instead of being simply dissipated at the moment of impact. In this 25 connection it will be noted that the conical

formation of the proximate faces of the sections of the cap tends to resist spreading of the sections and to that extent augments radial inertia of the metal and is in accord with that theory of the action of soft metal 30 caps.

The number of transverse sections in the cap may be varied, three being shown in the drawings, and while the hardness of the sections increases progressively toward the 35 point in the structure illustrated, it is not desired to limit the invention to this particular arrangement.

What is claimed is:

A cap for armor piercing projectiles 40 formed of a plurality of separate transverse sections of metal of successively increasing degrees of hardness toward the front end of the cap, the meeting faces of the sections being of forwardly directed conical formation and with the radial angle of the conical faces decreasing toward the front end 45 of the cap.

ALEXANDER G. MCKENNA.
WILLIAM DALTON.
